UNITED STATES PATENT OFFICE.

DANIEL JOSEPH MONTAMBO, OF MARINETTE, WISCONSIN.

STOVEPIPE AND CHIMNEY CLEANER.

No. 877,215.

Specification of Letters Patent.

Patented Jan. 21, 1908.

Application filed April 12, 1907. Serial No. 367,819.

To all whom it may concern:

Be it known that I, DANIEL JOSEPH MONTAMBO, residing in Marinette, in the county of Marinette and State of Wisconsin, have invented new and useful Improvements 5 in Stovepipe and Chimney Cleaners, of which the following is a description, reference being had to the accompanying drawings, which are a part of this specification.

10 This invention has for its object to provide a cleaner for stove pipes and chimneys which will effectively remove all soot and obstructions accumulating in the smoke passages while the fire is burning as well as 15 at other times.

15 Another object of this invention is to provide a blower for cleaning stove pipes and chimneys by forcing a strong current of air through the passageways to carry 20 with it the soot and other obstructions.

With the above and other objects in view the invention consists in the stove pipe and chimney cleaner herein claimed, its parts and combinations of parts and all 25 equivalents.

Referring to the accompanying drawings in which like characters of reference indicate the same parts in the several views; Figure 1 is a front elevation of a stove pipe and 30 chimney cleaner constructed in accordance with this invention, a portion of the casing cover being broken away to show the blower blades, and the open position of the cover being indicated in dotted lines; Fig. 35 2 is an end elevation thereof; Fig. 3 is a plan view with the cover removed; Fig. 4 is a side view of the cap for the branch pipe; and, Fig. 5 is a plan view thereof.

In these drawings 10 represents a stove 40 or other burner whose smoke pipe 11 is provided with a downwardly extending branch pipe 12 at a place where it is convenient to attach the blower of this invention.

45 A frame 13 supports a casing 14 having a hinged cover 15 forming therewith a cylindrical housing for a blower fan 16 which is journaled in the casing, the cover being provided with central openings to admit air 50 as usual and having a tangential spout portion 17 fitting in the branch pipe 12. A pinion 18 is mounted on the end of the shaft of the blower fan and meshes with a gear wheel 19 journaled in the frame, said 55 gear wheel being provided with a crank handle 20.

For convenience the shaft 21 on which the blower 16 is mounted may be reduced at the end distant from the pinion 18 and fitted into an undivided bearing 22, while 60 the other bearing 23 is a divided bearing fitting upon a reduced portion of the shaft. A catch plate 24 may be hinged to the free end of the cover 15 to engage a loop 25 of the casing to lock the cover in place. 65

In operation the gear wheel 19 is turned by means of its handle and by meshing with the pinion 18 causes the blower fan 16 to rapidly turn and force a strong current of air through the branch pipe 12 and the smoke pipe 11 and 70 the chimney with which it connects, this air current being of sufficient force to carry with it all soot and other obstructions in the passageways. This operation may be performed while the fire is burning in the stove 75 or other heater 10 without interfering therewith, the action of the current of air produced by the blower serving by induction to increase the draft through the stove rather than oppose it. 80

It is obvious that instead of the fan blower being driven through intermeshing gears as shown, belt pulleys and a driving belt may be substituted therefor, though the construction shown is preferred. When the cleaning 85 operation is completed the blower may be detached from the branch pipe 12 and a cap 26 substituted in place thereof so that the draft for the stove will not be interfered with. The cap 26 is provided with the usual bayonet joint connection by which it is securely held in place and is preferably provided with a central opening controlled by a pivoted cover plate 27 so that when the cover is open 90 the opening may act as a check draft for 95 the stove.

What I claim as my invention is;

1. A stove pipe and chimney cleaner, comprising a branch pipe leading to the stove pipe, a frame, a casing mounted thereon, a 100 cover for the casing connected with the branch pipe, a bearing on one side of the casing, a divided bearing on the other side of the casing, a shaft having a reduced end fitting in the first bearing and a reduced portion fitting 105 in the latter bearing, fan blades on the shaft, a pinion on the shaft outside of the casing, a gear wheel mounted on the frame and meshing with the pinion, a handle on the gear wheel, and a valved cap for closing the 110 branch pipe when the casing is disconnected therefrom.

2. A stove pipe and chimney cleaner, comprising a branch pipe leading to the stove pipe, a frame, a casing thereon, a blower fan journaled in the casing, a cover hinged to the 5 casing and adapted to removably connect with the branch pipe, means for securing the cover to the casing, means for turning the blower fan, and a valved cap for closing the

branch pipe when the casing is disconnected therefrom.

10 In testimony whereof, I affix my signature, in presence of two witnesses.

DANIEL JOSEPH MONTAMBO.
